UNITED STATES PATENT OFFICE.

FREDERICK W. HODGES, OF NEW YORK, N. Y.

HAT-HOLDER.

SPECIFICATION forming part of Letters Patent No. 642,447, dated January 30, 1900.

Application filed July 19, 1899. Serial No. 724,894. (No model.)

To all whom it may concern:

Be it known that I, FREDERICK W. HODGES, of the city of New York, borough of Manhattan, in the county and State of New York, have invented a new and Improved Hat-Holder, of which the following is a full, clear, and exact description.

This invention relates to a hat-holder adapted to be applied to chairs beneath the seats thereof so that hats may be held in such position, the object being to provide a device which may readily be attached to any chair of the ordinary construction.

This specification is the disclosure of one form of my invention, while the claims define the actual scope thereof.

Reference is to be had to the accompanying drawings, forming a part of this specification, in which similar characters of reference indicate corresponding parts in both the views.

Figure 1 is a perspective view of the invention in use; and Fig. 2 is a plan view of the invention, showing the legs of the chair in section.

I prefer to construct the hat-holder of an integral length of spring-wire bent to form the main or side portions *a*, bowed inwardly, and each terminating in approximately horse-shoe-shaped loops *b* and *c*, forming spring-clamps. The loops or clamps *b* are respectively at the ends of the length of wire referred to, and when the holder is in place these loops *b* engage the front legs, as shown. The loops *c* engage the rear legs, and from the loops or clamps *c* the intermediate portion of the wire is bent inward and forward, forming arms *d*, connected by a curved cross-piece *e*.

The arms *d* and the cross-piece *e* are held by the resiliency of the wire in the position shown, and the hat is held in place by being strung between the middle portions of the sides *a* and against the cross-piece *e*, as indicated in Fig. 1. The hat when so engaged with the holder is supported securely and without injury to the hat. The device may be readily attached to and detached from the

chair by springing the clamps *b* and *c* over the legs in the manner shown.

As shown in the drawings, the arms *d* are passed over the side portions *a* of the holder and then are passed down under the same to join with the cross-piece *e*. I prefer this arrangement, since it produces a durable compact structure.

By means of the construction shown the hat is held securely and cannot be removed except from the front of the chair, which prevents persons from taking the hat without the knowledge of the owner.

Having thus fully described my invention, I claim as new and desire to secure by Letters Patent—

1. A hat-holder, comprising open loops of resilient material, the loops forming spring-clamps to engage the legs of a chair, and means attached to and supported by the loops to engage and hold the hat.

2. A hat-holder, comprising spring-clamps serving to engage the legs of a chair to support the hat-holder beneath the seat thereof, and means carried by the clamps for engaging and supporting the hat.

3. A hat-holder formed of an integral length of spring-wire bent to form two inwardly-bowed side portions each terminating in spring-clamps serving to engage the legs of a chair, the wire having its intermediate portion bent to form two forwardly-projecting arms joined by a curved cross-piece, the hat being held between the said portions and against the cross-piece.

4. A hat-holder formed of an integral length of spring-wire bent to form two side portions each terminating in a spring-clamp serving to engage the legs of a chair, the intermediate portion of the wire being extended forwardly, and a cross-piece between the side portions which hold the hat.

FREDERICK W. HODGES.
